Patented Dec. 5, 1922.

INVENTOR

JOSEPH E. IVAN LEWIS

BY

H. E. K. Henderg

ATTY

UNITED STATES PATENT OFFICE.

JOSEPH E. IVAN LEWIS, OF HAMILTON, ONTARIO, CANADA.

HOLDUP PROTECTIVE DEVICE.

Application filed May 8, 1922. Serial No. 559,340.

To all whom it may concern:

Be it known that JOSEPH E. IVAN LEWIS, a subject of the King of Great Britain, residing at Hamilton, in the county of Wentworth and Province of Ontario, Canada, has invented certain new and useful Improvements in a Holdup Protective Device, of which the following is a specification.

My invention relates to improvements in hold-up preventative devices, and particularly to such devices as will be adapted for use in offices and the like, and consists essentially of a stand to be concealed under a desk and having a pistol mounted in such manner as to be aimed and fired with the foot.

The principal object of the invention is to provide a device to outwit a bandit in an attempt to hold up an office staff and assure his capture or apprehension.

A further object is to provide an arrangement whereby a pistol or other suitable firearm may be mounted in a concealed position within a desk and having means for aiming and firing without attracting the suspicions of a bandit as to the operator's intentions, when the bandit is in the act of covering the operator with his firearm, the operator's hands being in elevated position as is customary in such proceedings, and consequently unable to defend in an otherwise competent manner.

A still further object is in the provision of novel means for visibly aiming the concealed pistol without detection of the bandit.

These, together with other objects, may be attained by the construction, combination and arrangement of the parts as will be hereinafter more fully described; illustrated in the accompanying drawing, and pointed out in the claims hereunto appended.

Referring to the drawings:

Figure 1 is a perspective view of the complete apparatus shown in concealed position in a desk which is perspectively illustrated in cross-section; and,

Figure 2 is a side elevation of the device on an enlarged scale.

Similar reference characters refer to similar parts throughout both views.

The stand comprises two rear standard rods 2 and a forward standard rod 3 rigid on the fixed base 4 and supporting a plate 5 upon which is mounted a three legged additional supporting member including a second plate 6.

A perpendicularly disposed shaft 7 is adapted to rotate in a socket 8 fixed to the base 4, and passes through holes in the plates 5 and 6 which form bearings therefor. This shaft is retained in perpendicular relation by the nut 9 threaded on the lower end thereof beneath the socket 8.

On the upper end of said shaft is formed a clamp 10 adapted to rigidly hold the barrel 11 of a pistol or other suitable firearm, as shown, and which clamp may be tightened around the said barrel by the clamp screw 12.

An expansion member is formed of twin metal straps 13 having rigid connection one to the other at one end by a short rod 14 which passes intermediately through the trigger guard 15 of the pistol immediately forward of the trigger 16. The opposite end parts of these straps are pivotally connected to links 16' which in turn are pivotally connected at their opposite ends to opposed laterally extending arms 17 on the shaft 7.

Normally this expansion member assumes an obtuse angular position, the pivotal connection of the straps 13 and the links 16 forming an apex which is above the opposite ends of said straps and links.

The rod 14 projects beyond the outsides of the straps 13, and these outward projections are adapted to horizontally slide in the guides comprised of rods 18 bent over parallel and rigidly secured to the arms 17.

A treadle 19 is loosely connected to the socket 8, as shown, the end of the treadle bar being formed into a hook 20 which links with an eye 21 in said socket. The treadle 19 is connected by suitable means, such as a cable 22 as shown, for example, to the pivotal connection between the straps 13 and links 16'. A rudder 23 is formed at the end of a rod 24 rigidly secured to the shaft 7, above the treadle 19.

The device is positioned beneath the table A of the desk directly in the rear of the front panel B thereof, where the treadle 19 and rudder 23 are within easy reach of the feet of the person sitting at the desk.

Extending upwardly from one of the members of the clamp 12 and rotatable with the pistol and shaft 7 is a vertical rod 25 having rigidly mounted thereon an aim indicator preferably in the form of an arrow or pointer 26 which is set to register the direction in which the pistol is pointing.

2
Directly over this arrow or pointer 26 I remove a section of the table A and provide or substitute a section of glass 27 or other suitable transparent material flush with the 5 surface of said table and through which the arrow or pointer 26 is visible.

A portion of the front panel B of the desk in the firing range of the pistol is removed, and inserted in its place is a section 28 of 10 material which is sufficiently penetrable not to deflect or to retard a bullet projected from the pistol, preferably consisting of what is known to the builder's trade as "beaver board", for example, and that which may be 15 finished to correspond with the finish of the desk.

The fire-arm is aimed by feel of the foot against the rudder 23, and fired by pressure with the same foot upon the treadle 19 sub- 20 sequently to sight being located by the pointer 26.

Having now fully described my invention, what I claim and desire to secure by Letters Patent, is:—

25 1. In a device of the class described, a fixed stand, a rotatable member, a fire-arm rigid on said rotatable member, trigger operating mechanism, a foot treadle connected with said trigger operating mechanism, and 30 means for aiming the fire-arm by revolving said rotatable member by means of the foot.

2. In a device of the class described, a fixed stand, a rotatable member, a fire-arm rigid on said rotatable member, a foot 35 treadle, an expandible member positioned between said rotatable member and the trigger of said fire-arm, a cable connecting said expandible member with said foot treadle adapted to expand said expandible member 40 against the trigger when said foot treadle is depressed.

3. In a device of the class described, a fixed stand, a rotatable member, a fire-arm rigid on said rotatable member, a foot 45 treadle, an expandible member positioned between said rotatable member and the trig-

ger of said fire-arm, a cable connecting said expandible member with said foot treadle adapted to expand said expandible member against the trigger when said foot pedal is 50 depressed, and a rudder rigid with said rotatable member adapted to move said rotatable member in either direction by touch of the foot.

4. In a device of the class described, a 55 desk or counter having a front panel and leg space beneath the desk top, a stand fixed beneath the desk top and in said leg space, a rotatable member journalled in said stand, a fire-arm rigid on said rotatable member, trigger operating mechanism, a foot treadle connected with said trigger operating mechanism, a rudder rigid on said rotatable member above said foot treadle, a direction indicator fixed at top of said rotatable member 60 and pointing in the same direction as the fire-arm, and a transparent panel inserted in said desk top over said direction indicator.

5. In a device of the class described, a 70 desk or counter having a front panel and leg space beneath the desk top, a stand fixed beneath the desk top and in said leg space, a rotatable member journalled in said stand, a fire-arm rigid on said rotatable member, trigger operating mechanism, a foot treadle 75 connected with said trigger operating mechanism, a rudder rigid on said rotatable member above said foot treadle, a direction indicator fixed at top of said rotatable member and pointing in the same direction as the 80 fire-arm, a transparent panel inserted in said desk top over said direction indicator, and an easily penetrable panel section inserted in the front panel of the desk in range of said fire-arm.

85

In testimony whereof I have affixed my signature.

JOSEPH E. IVAN LEWIS.
